CHARLES S. LABOFISH, OF WASHINGTON, DISTRICT OF COLUMBIA, ASSIGNOR TO UNION TYPEWRITER COMPANY, OF JERSEY CITY, NEW JERSEY, A CORPORATION OF NEW JERSEY.

TYPE-WRITING MACHINE.

No. 909,616.

Specification of Letters Patent.

Patented Jan. 12, 1909.

Application filed July 20, 1903. Serial No. 166,294.

To all whom it may concern:

Be it known that I, CHARLES S. LABOFISH, citizen of the United States, and resident of Brightwood Park, Washington, in the District of Columbia, have invented certain new and useful Improvements in Type-Writing Machines, of which the following is a specification.

My invention relates more particularly to tabulating devices for typewriting machines and it consists in certain parts and combinations which will be particularly described herein and set forth in the appended claims.

My invention is illustrated in the accompanying drawings in which,

Figure 1 is a front elevation of so much of a typewriter as is necessary to illustrate my improvements, the key board being shown in vertical section on the line $x-x$ of Fig. 2. Fig. 2 is a vertical longitudinal section through the machine. Fig. 3 is a perspective view of the carriage feed device. Fig. 4 illustrates a detail. Fig. 5 is a horizontal section, partly broken away, through the key board. Fig. 6 is a detail end elevation, a shaft being shown in section. Fig. 7 is a perspective view of a frame forming part of my device.

My invention is applicable to various forms of typewriting machines, but for the purpose of illustration I have shown it as embodied in a Smith Premier typewriter, this being a form of writing machines well known.

The typewriting machine comprises a main frame 1 upon the upper part of which slides a paper carriage 2 having a cylindrical platen 3. The type bars 4 are mounted in circular arrangement about the printing point and are rigidly fastened to oscillating shafts 5 having crank arms 6 connected by links 7 to crank arms 8 on shafts 9 oscillated in one direction by keys 10 through the medium of crank arms 11 and returned to normal position by springs 12. The key stems slide in frame pieces or guides 13 and have upon their upper ends the usual buttons 14 bearing characters corresponding to the characters upon the respective types. A frame bar or plate 15 extends across the back of the machine and forms the end support for the several shafts 9 each of which has near its rear end an eccentric projection 16 in contact with a frame 17 mounted to have reciprocating motion upon said plate

15, (see Fig. 4). The construction is such that whenever any key is depressed the frame 17 will receive a slight lateral movement and thus oscillate a bell crank lever 18 pivoted to the plate 15 at 19 and pivotally connected to the frame 17 at 20. To the other arm of said bell crank is pivoted a link 21 connected to a crank arm 22 fixed to an oscillating shaft 23 journaled in a projection from the main frame. Fixed to the other end of said shaft is a member 24 having a toe 25 and a projection or dog 26. A dog 27 is pivoted to the main frame at 28 and carries a set screw 29, the lower end of which stands over the toe 25.

The dog 27 and the dog or projection 26 together constitute an escapement co-operating with a rack bar 30 forming part of the carriage. The said carriage is drawn in a transverse direction by a spring which is enclosed in and actuates a drum a , which is connected to the carriage by a strap b . Whenever a key is depressed and the frame 17 is reciprocated, the shaft 23 is oscillated, depressing the projection 26 into the path of one of the teeth of the ratchet and lifting the dog 27 out of engagement with one of said teeth and letting said dog come into engagement with the next tooth of the series upon the release of the key.

A bar 31 is pivoted to the carriage at 32 and is normally held in the position shown in Fig. 2 by a spring 33. A projection 34 from the dog 27 stands over this bar so that if the bar be raised, the dog 27 will be lifted from engagement with the rack and the carriage be freed from its escapement mechanism. The bar 33 is lifted for this purpose by a release key 35 pivoted to one of the end frame bars of the carriage at 36 and having a finger piece 35' by which it may be conveniently depressed. The machine as thus far described, is old and well known in the art.

To the front of the paper carriage I attach a screw threaded rod 37 by means of arms 38 projecting from the carriage. Upon this rod I mount a stepped cone 39 having internal screw threads so that it can be given any position lengthwise of the rod by turning it as a nut. As shown the cone 39 is formed with ten square shouldered steps. A stop 40 is slidably mounted in the frame of the machine and provided with means whereby it may be adjusted vertically so as

to coöperate with any one of the steps of the cone 39 to stop the carriage in any one of a number of different positions. The steps of the cone have a lateral width equal to the letter space of the machine, that is to say, equal to the distance apart of the teeth of the rack 30. The stop 40 may be adjusted vertically differential distances to coöperate with any one of the steps of the cones by means of a differential mechanism which will now be described.

Beneath the key board, and extending from right to left near the first row of keys, I provide a bar 41 slidably mounted upon rods or screws 42 by means of bearings 43. The rods 42 are fixedly mounted in the frame of the machine and have springs 44 coiled about them and compressed between a portion of the frame work and the bearings 43, thus pressing the bar 41 toward the front of the machine. The bearings 43 have slots 45 through which extend levers 46 and 47 pivoted upon the respective rods 42. The levers 46 and 47 are formed with graduated 20 projections 48 extending through slots 49 in the bar 41. The bar 41 is provided with a series of projections 50, one for each of the slots 49. The levers 46 and 47 are provided upon their inner ends with vertically arranged 25 segmental racks 51 and 52 respectively, and are normally held in an elevated position by springs 53 supported by hangers 54 depending from the bar 41. The racks 51 and 52 are adapted to engage a horizontally 30 arranged elongated pinion 55 but are normally held out of engagement with said pinion by the springs 53. The bar 41 has a vertical projection 56 to which is connected a push key 57 projecting through the front of 35 the key board casing and by which the frame may be pushed against the tension of the springs 44 to its rearward position. The projections 48 and 50 are so arranged that when the frame is thus pushed to its 40 rearward position each of the projections 48 comes under the crank arm 11 connected with one of the keys of the first row and the projections 50 also come under said 45 crank arms.

It is obvious that if the frame 41 be moved to its rearward position by means of the key 57 and one of the keys 10 be then depressed, said key will depress the lever 46 or 47 through its projection 48 and the downward 50 motion of the key will be limited by the contact of the arm 11 with the projection 50 which thus determines the exact distance the key can be depressed, which distance, however, is not sufficient to cause the type 55 to print. The projections 48 and 50 are so proportioned that the different keys give different degrees of motion to the racks 51 and 52 and oscillate the pinion 55 to different extents.

The pinion 55 is journaled at its front end

in the key board framework and at its rear end in a frame piece 58 attached to the main frame of the machine at 59 and to the key board frame work at 60. The stop 40 is the upper end portion of a slide 61 mounted to 70 have a reciprocatory movement on the frame piece 58. The slide 61 is guided on the frame piece 58 by guides 62 and is formed with laterally projecting lugs 63 and 64. These lugs are engaged by slides 65 and 66 75 also mounted upon the frame piece 58 and provided with rack teeth 67 and 68 respectively. These rack teeth are in mesh with a pinion fixed to the same shaft as pinion 55, or, in the form shown in the drawings, 80 with a prolongation of said pinion 55. The slide 61 is drawn towards its lower position by a spring 69 attached at one end to said slide and at the other end to the frame piece 58. It is obvious that the racks 51 and 52 85 oscillate the pinion 55 in opposite directions. When the rack 51 is depressed the pinion 55 is oscillated to the left, as shown in the drawings, with the result that the bar 66 is elevated and the bar 65 depressed. Whereas 90 if the rack 52 is depressed the pinion is turned to the right and the bar 65 is elevated and the bar 66 depressed. In either event the slide 61 is elevated, and as before remarked, the different keys are arranged to 95 elevate the slide different distances.

The bar 41 may be conveniently constructed as shown, of sheet metal in which case the bearings 43 are made by bending the ends of the metal as shown, and the projections 50 are formed by striking up the material from the slots 49 and the projections 54 and 56 may be formed by appropriately shaping the sheet metal and bending the projections as shown most clearly in Fig. 7. 100

Upon its opposite edges near the upper end the slide 61 is provided with rack teeth 70 coöperating with pinions 71 journaled on pins or screws projecting from the main frame of the machine. Integral with said 105 pinions are cams 72 having grooved faces 73 coöperating with a yoke shaped frame or bail 74 attached at one end to the release key 35 and at the other end pivoted to the carriage. Whenever the slide 61 is elevated 110 the pinions 71 are rotated and the cams 72 depress the yoke 74 and thus operate the release key to release the carriage from its escapement mechanism.

It will be observed that for the purpose 115 of operating my tabulating device I utilize some of the ordinary keys of the machine. Normally the sliding frame 41 is in such a position that it does not interfere with the use of the keys for writing purposes and the 120 projections 48 and 50 cannot be struck by the keys; but when the key 57 is pushed in, the tabulating device is brought into position to be operated by certain of the writing keys. In the present instance I have shown 125 130

ten of the keys of the first row as coöperating with the tabulating device. The buttons of these keys may be provided with characters such as ".","1","10","100", &c., 5 up to hundreds of millions, to indicate to which denominational position each key is adapted to bring the carriage. I prefer, however, that the character keys used for this purpose be the numeral keys of the typewriter, the several buttons 14 of which bear the characters "0", "1", "2", "3", "4", "5", "6", "7", "8", and "9", corresponding to the character which each key is adapted to print. When the frame 41 is pushed under 10 the keys, these characters indicate the denominational positions to which the several keys are adapted to bring the carriage, the "0" key being for the decimal point, the "1" key for units place, the "2" key for 15 tens place, etc.

The parts are so graduated that the key 76 elevates the stop 40 the shortest distance of any key, thus bringing it into position to be struck by the longest or outermost step 25 75 of the cone 39. The key 77 elevates the stop 40 a little higher bringing it into the path of the step 78 of the cone 39, and so on across the machine, each succeeding key corresponding to a successively lower step on 30 the cone.

In the operation of my device, the largest step 75 of the cone 39 is adjusted according to the carriage scale 79 to the position in which it is desired to write the decimal point. 35 If, then, it is desired to bring the carriage to this position, the key 57 is pushed in and the key 76 depressed until it is stopped by its projection 50. This turns the pinion 55 to a slight extent to the left thus elevating the 40 slides 66 and 61 and the stop 40. This motion of the slide 61 turns the cams 72, depressing the yoke 74 and release key 35, thereby releasing the carriage, whereupon the carriage is drawn to the left by the strap 6 and 45 stopped by contact of the step 75 with the stop 40. If the first figure of the number to be written is in some denomination, such as units, tens, etc., the operation is the same except that the key corresponding with that 50 denomination is depressed instead of the key 76.

The scale 79 is the ordinary carriage scale of the machine and is read by reference to my index finger 80. It will be observed that 55 my tabulator is arranged in front of the machine where it is convenient for manipulation by the operator and that the stop cone 39 may be readily adjusted on its rod by reference to the said carriage scale 79, which 60 lies behind said cone.

While I have described the preferred embodiment of my invention, I am aware that many modifications may be made without departing from the spirit of my invention. 65 For example, it is not absolutely essential

that the conical nut 39 should be circular in cross-section, although in the present case I prefer the form shown. So far as I am aware, it is new to provide a denominational stop device in the form of a threaded nut 70 with any form of stepped faces at different distances from the axis of the nut.

It has been common heretofore to locate the denominational stops either on the carriage or on the frame of the machine and to 75 locate the coöperating tabulating stop or stops accordingly. I do not, therefore, wish to be understood in all cases to be confined as to the location of the denominational and tabulating stops.

Some of the features set forth in the present application are also shown and are more broadly claimed in my prior applications, Serial No. 42,676, filed January 9th, 1901; Serial No. 53,670, filed March 30th, 1901 85 and Serial No. 127,412, filed October 15th, 1902.

What I claim as new and desire to secure by Letters Patent, is —

1. In a typewriting machine, a carriage 90 stop having the form of a stepped conoidal block, in combination with a coöperating stop.

2. In a typewriting machine, a stop piece having the form of a conoidal block, and a 95 stop coöperating with said stop piece; said stop and stop piece being adjustable the one with reference to the other.

3. In a typewriting machine, a stop piece having the form of a stepped conoidal block, 100 and a stop coöperating with said stop-piece; said stop and stop-piece being adjustable, the one with reference to the other, to cause the stop to coöperate with any desired step of said stop-piece.

4. In a typewriting machine, the combination with a main frame, and a carriage movable across said main frame, of a tabulator comprising two members; one on the main frame and one on the carriage; one of said 110 members being a stop and the other a conoidal stop-piece; said members being adjustable, the one with reference to the other.

5. In a typewriting machine, the combination with a main frame, and a carriage movable across said main frame, of a tabulator comprising two members; one on the main frame and one on the carriage; one of said members being a stop and the other a conoidal stop-piece; one of said members being 115 adjustable towards and from the other; and one of said members being adjustable in a direction parallel to the direction of movement of the carriage.

6. In a typewriting machine, the combination with a main frame, and a carriage movable across said main frame, of a tabulator comprising two members; one on the main frame and one on the carriage; one of said members being a stop and the other a co- 120

- 15 noidal stop-piece; and means for adjusting one of said members toward and from the other.
- 16 7. In a typewriting machine, the combination with a main frame and a carriage movable across said main frame; of a tabulator comprising two members, one on the main frame and the other on the carriage; one of said members being a stop and the other a 10 conoidal stop-piece; one of said members being adjustable toward and from the other; and said conoidal stop-piece being adjustable along a rod, parallel to the direction of motion of the carriage.
- 17 8. In a typewriting machine, the combination with a main frame and a carriage movable across said frame, of a denominational tabulator comprising a stepped conoidal stop adjustable in a direction parallel to the 20 direction of motion of the carriage; a stop coöperating with said stepped stop; said stop and stepped stop being adjustable, the one toward and away from the other to cause the stop to coöperate with any desired step 25 of the stepped stop; and printing keys that are adapted to effect the relative adjustment of said stops to bring them into coöperation.
- 18 9. In a typewriting machine, a tabulator comprising a rod; a stop-block adjustable 30 along said rod and having a stepped conoidal form; a stop capable of coöperating with any one of the steps of the stop-block according to the distance apart of the stop and the rod; and means for varying such 35 distance at will.
- 19 10. In a typewriting machine, the combination with a carriage, of means for arresting said carriage in different positions comprising a rod, a conical stop-block adjustable 40 on said rod; and a stop for said conical stop-block adjustable differential distances from said rod.
- 20 11. In a typewriting machine, a denominational tabulator comprising a screw-threaded rod; a nut on said screw-threaded rod having stepped stop surfaces arranged 45 at different distances from the axis of the rod and at different points along said axis; and a stop capable of coöperating with any one of said stop surfaces.
- 21 12. In a typewriting machine, a denominational tabulator comprising a screw-threaded rod; a nut on said rod having a stepped surface; and a stop capable of coöperating with any one of the steps of the 50 ut.
- 22 13. In a typewriting machine, a tabulator comprising a screw-threaded rod; a nut on said rod having a stepped conoidal form; a 55 stop capable of coöperating with any one of the steps of the nut according to the distance apart of the stop and the rod; and means for varying such distance at will.
- 23 14. In a typewriting machine, the combination with a carriage, of means for arrest- 60 ing said carriage in different positions comprising a screw-threaded rod, a conical nut on said screw-threaded rod, and a stop for said conical nut adjustable differential distances from said rod.
- 24 15. In a typewriting machine, the combination with a carriage, of means for arresting said carriage in different positions comprising a screw-threaded rod, a nut in the form of a stepped cone, an adjustable 65 stop, and a differential mechanism for adjusting said stop into position to coöperate with any desired step of the cone.
- 25 16. In a typewriting machine, the combination with a main frame and a carriage movable thereon, of means for arresting said carriage in different positions comprising a threaded rod fixed to the carriage, a nut on said rod in the form of a stepped cone, a stop mounted on the main frame and movable toward and away from said rod, and a differential mechanism for adjusting said stop to coöperate with any desired step of the cone.
- 26 17. In a typewriting machine, the combination with a carriage and means for moving the same, of a device permitting a step-by-step motion of the carriage, a tabulating device comprising an adjustable stop, a rack movable with said adjustable stop, a rotary 85 cam operated by said rack, and means operated by said cam for disengaging the step-by-step device and releasing the carriage.
- 27 18. In a typewriting machine, the combination with a carriage having a release key, 90 of a tabulating device comprising a rack, a rotary cam operated by said rack, and means operated by said rotary cam for operating the release key.
- 28 19. In a typewriting machine, the combination with a carriage having a release key, 95 of a bail mounted on the carriage and coöperating with the release key; a tabulating device comprising a key controlled stop carried by the stationary framework, and means operated by said stop to operate said bail.
- 29 20. The combination of a pinion; means for imparting differential movements to said pinion in either direction; two racks, one on each side of said pinion; and a member receiving differential motion from one or the other of said racks, according to the direction in which the pinion is moved.
- 30 21. The combination of a pinion; means for imparting differential movements to said 100 pinion in either direction; two rack bars, one on each side of said pinion; and a sliding reciprocating member adapted to receive differential movements from one or the other of said rack bars, according to the 105 direction in which the pinion is moved.
- 31 22. The combination of a shaft; two operating racks, one on either side of said shaft; means for imparting differential movements to either of said racks; and a member re- 110

ceiving differential movement from said shaft when either of the racks is moved.

23. The combination with a member to which differential movements are to be imparted, of two levers having their pivots at a distance apart; keys for imparting differential movements to either of said levers; and means intermediate said pivots for conveying the motion of either lever to said member.

24. The combination with a member to which differential movements are to be imparted, of two levers, each having a rack on its free end; a series of keys for imparting differential movements to either of said levers; a pinion turned in one direction by one of said racks and in the other direction by the other; and means for conveying the motion of said pinion to said member.

25. In a typewriting machine, the combination of a row of keys; two levers pivoted near the two ends of said row respectively and having their free ends near the middle of the row; said levers adapted to be operated by said keys, and a carriage stop controlled by the free end of either lever.

26. In a typewriting machine, the combination of printing keys, a pivoted lever adapted to be operated by any of said keys and having a rack fixed on its free end, a pinion operated by said rack, and a carriage stop controlled by said pinion.

27. The combination of a pinion; means for imparting differential movements to said pinion in either direction; two racks, one on each side of said pinion; and a carriage stop receiving differential motion from one or the other of said racks, according to the direction in which the pinion is moved.

28. The combination of a shaft; two operating racks, one on either side of said shaft; means for imparting differential movements to either of said racks; and a carriage stop receiving differential movement from said shaft when either of the racks is moved.

29. The combination with a carriage stop to which differential movements are to be imparted, of two independently movable levers having their pivots at a distance apart; keys for imparting differential movements to either of said levers; and means intermediate said pivots for conveying the motion of either lever to said carriage stop.

30. The combination with a carriage stop to which differential movements are to be imparted, of two levers, each having a rack on its free end; a series of keys for imparting differential movements to either of said levers; a pinion turned in one direction by one of said racks and in the other direction

by the other; and means for conveying the motion of said pinion to said carriage stop.

31. In a typewriting machine, the combination with a series of keys, of a tabulating device comprising a frame having fixed parts adapted to limit the motion of the keys, and mounted to slide rectilinearly into and out of co-operative relation to the keys, a plurality of independently operable levers controlled by said keys, and a stop device controlled by said levers.

32. In a typewriting machine, the combination with a row of keys and printing devices operated by said keys; of a tabulating device comprising a frame having a sliding bearing on a rod, a slot in said bearing, and a lever extending through said slot and pivoted on said rod and adapted to be operated by said keys.

33. In a typewriting machine, the combination with a carriage stop and a rotary shaft for operating the same, of a row of keys extending in a direction transverse to said shaft; a frame slidable in a direction parallel with said shaft toward and away from said row of keys; a lever movable with said frame and adapted when in one position to be operated by said keys; and a rack carried by said lever and adapted to rotate said shaft.

34. In a typewriting machine, the combination with a series of keys, of a frame supported beneath said keys; levers extending beneath said frame and having projections extending above said frame to co-operate with the keys; stops on said frame for limiting the movement of the keys; racks on the ends of said levers; a pinion adapted to be turned by either of said racks; and a carriage stop operated by said pinion.

35. In a typewriting machine, the combination of a main frame; a frame slidably mounted on said main frame; a lever pivoted at each end of said sliding frame and extending toward the middle thereof; a series of keys adapted to operate said levers when the sliding frame is in one position but free of the same when the sliding frame is in the other position; a pinion journaled in the main frame and lying between the free ends of the levers; racks on the free ends of the levers; and a carriage stop operated by said pinion.

Signed at Brightwood Park, Washington, D. C., this seventeenth day of July A. D. 1903.
